UNITED STATES PATENT OFFICE.

EDGAR H. MUMFORD, OF PHILADELPHIA, PENNSYLVANIA.

METHOD OF JOLT-RAMMING MOLDS.

980,994.

Specification of Letters Patent. Patented Jan. 10, 1911.

Application filed February 15, 1910. Serial No. 544,005.

To all whom it may concern:

Be it known that I, EDGAR H. MUMFORD, a citizen of the United States, residing at Philadelphia, in the county of Philadelphia and State of Pennsylvania, have invented 5 certain new and useful Improvements in Methods of Jolt-Ramming Molds, of which the following is a specification.

This invention has reference to an improved method of jolt ramming molds, and it has for its primary objects, the prevention of the uneven wear of plunger and cylinder commonly incident to work of this character, resulting from the fact that the molds are 10 generally placed upon the jolt ramming tables without proper regard to the location of the centers of gravity which produces over turning action, or tendency to distortion of the lifting plunger in its cylinder resulting in uneven wear in the plunger that 15 raises the table and guides it in its downward fall. In order that my invention may be better understood I have prepared a drawing, which forms a part of this specification, 20 and wherein—

Figure 1 is a perspective view with a portion of the mold broken away, the mold being placed in position upon a wedge for a purpose which will hereinafter be more particularly described, and Figure 2 is a view 30 partly in section, showing the upper end of the plunger and jolt ramming table mounted on the plunger, with a mold set upon the table in position to be jolt rammed.

In carrying out my invention, I first take 35 a mold formed by the use of a pattern board 3, having the pattern 4 located thereon, and the flask 5 in position on the board, the mold part being formed with the sand within the flask either compacted or ready to be compacted properly about the pattern, as indicated in Figure 1, where the sand is partly broken out, as is also one portion of the flask in order to show the pattern. This 40 mold part, I first set upon a straight edge 7 in a position substantially such as is shown in Figure 1, moving it back and forth until it balances thereon, then forming a mark or notch at 8 upon each of the opposite edges,

where the board rests upon the straight edge, after which the mold is turned around through an angle and balanced again on the straight edge, obtaining two other marks, one of which is shown at 9, said last mentioned marks being on the other two sides 50 of the board, after which by connecting the

marks on the edges and finding where the lines connecting the same will cross, as at 10, I am enabled to locate the point on the under or impact face of the board which will be 60 directly under the center of gravity of the completed mold.

The mold table is indicated at 11 in Figure 2, and the plunger at 12, the latter working in the cylinder 13, which plunger and cylinder may be of any preferred construction. The upper face of the table is provided with some means for locating or positioning the mold, such for example as the upstanding lug 14, and on the under side of 70 the board 3 I make a recess just adapted to fit over the lug 14 in the position shown in Figure 2, the center of such recess being located by the crossing of the two lines at the point marked 10.

From the foregoing it will be evident that in carrying out my invention, I am enabled to get the mold placed on the jolt ramming table with the center of gravity of the mold, or the approximate center of gravity 80 of the mold, directly over the center of the impact surface, on which account there is not any appreciable lateral stress or tendency to tilt or unevenly wear the plunger in the jolt ramming operation, whereas if the mold be placed at random upon the table, or if it be placed with the center of area of this mold over the center of the table, there will be lateral strains and tilting tendency due to the fact that the center of gravity is out of line with the center of the plunger or impact surface. While I have shown the upstanding lug 14 directly over the center of the table, it is obvious that it or a number of lugs might be otherwise located, 90 provided only that these are made in such way as to hold the mold in proper position, the essential thing being that the center of gravity of the mold complete, should come approximately over the center of the impact surface, or in such position with relation to the table and the jolt ramming mechanism, as will avoid tilting and other unequal strains, however it may be set and secured there.

Most molds and cores are of unevenly distributed weight and are practically never set so that the weight on the table of the machine does not tend to tip it in one direction or another.

Such tipping causes plungers to wear in their cylinders—at both ends.

In large machines this tipping and wearing moment is very considerable and many machines installed within the last few years are already worn out from this cause.

5 Having thus described my invention and illustrated its use what I claim as new and desire to secure by Letters-Patent is the following:—

- 10 1. The herein described method of jolt ramming molds which consists in locating a point under the face of the mold directly under the center of gravity of the mold and then securing the mold upon a jolt ramming apparatus with the center of gravity thereof directly over the center of application of the jolt ramming mechanism.
- 15 2. The herein described method of jolt ramming molds which consists in placing the mold upon a jolt ramming apparatus with the center of gravity of the mold, directly over the center of the resistance sur-

face which checks the downward movement of the mold.

3. The herein described method of jolt ramming molds which consists in ascertaining by test the vertical line in which the center of gravity of the mold lies, fixing the location of such line with respect to the pattern plate, mounting the pattern plate and mold upon a jolt ramming machine with the said line in substantial alinement with the axis of the rammer plunger, jolt ramming the mold, and maintaining the mold against lateral movement during such ramming.

25 35 In testimony whereof I have hereunto set my hand before the two subscribed witnesses.

EDGAR H. MUMFORD.
